UNITED STATES PATENT OFFICE.

BOY H. NOE, OF MEMPHIS, TENNESSEE.

EXERCISING APPARATUS.

Application filed October 28, 1925. Serial No. 65,402.

My invention relates to improvements in exercisers of that type which comprises one or more elastic members connected at the ends thereof to a pair of handles, and it consists in the combinations, constructions and arrangements herein described and claimed.

An object of the invention is the provision of an exerciser of the character described which has simple, reliable and quickly and easily adjusted means for connecting the ends of a single strip of elastic material or the ends of any predetermined number of superposed strips of elastic material within a considerable range with a pair of hand grip members so that the resistance of the exerciser to any force tending to modify the normal form of the elastic member or members thereof can be varied at will by varying the number of elastic strips which are connected with the hand grip members.

A further object of the invention is the provision of an exerciser of the character described which affords facilities for connecting the opposite ends of a plurality of superposed strips of elastic material to hand grip members so that any pull on the elastic strips as a result of movement of the hand grip members apart or away from each other will be resisted equally by the respective elastic strips provided that the elastic strips are of the same size and have the same elastic strength.

A still further object of the invention is the provision in an exerciser of the character described of handle units comprising clamping means for holding corresponding ends of a plurality of superposed strips of elastic material firmly clamped together without undue pressure on any one of the elastic strips and without injury to the elastic strips.

Other objects and advantages of the invention will be apparent from the following description, considered in conjunction with the accompanying drawings, in which

Figure 1 is a view showing an exerciser embodying the invention in use.

Figure 2 is a relatively enlarged fragmentary perspective view of the improved exerciser.

Figure 3 is a section along the line 3—3 of Fig. 2.

In carrying out the invention, I make use of one or more elastic strips 1. Each strip 1 is made of sheet material possessing desir-

able elasticity, preferably rubber. The respective strips 1, when more than one strip is employed, preferably have exactly the same corresponding dimensions and the same elasticity.

The invention provides a pair of handle units generally indicated at 2. Each handle unit comprises a hand grip member 3 which preferably is substantially circular in cross sectional contour. Each hand grip member 3 is joined integrally at its ends to a pair of side bars 4 which are joined integrally to the ends of a clamp member or jaw 5, the latter thus being disposed parallel to the hand grip member 3. The clamp member 5 has a flat upper face indicated at 6 which lies in a plane that extends through the hand grip member 3 below the center line of the latter. The clamp member 5 also has upstanding stud projections 7 rigid therewith adjacent to opposite ends thereof. Each handle unit also comprises a second clamp member or jaw 8 having the form of a substantially flat bar formed with vertical openings in the end portions thereof through which the stud projections 7 may extend. The clamp member 8 has a flat bottom face, indicated at 9 in Figure 3. The clamp member 8 may be reinforced by a longitudinally extending integral stiffening rib 10 on the upper face thereof. Nuts 11 threadedly engage the extending upper end portions of the stud projections 7 and prevent displacement of the upper clamp member 8 from a desirable position with respect to the lower clamp member 5.

From the foregoing description of the various parts of the device, the operation thereof may be readily understood. One or more strips 1 can be employed in conjunction with the handle units 2 at a given time. The ends of the strip or strips are extended between the members of the clamps of the respective handle units, the nuts 11 having first been loosened sufficiently to permit the end portions of the strips to be readily projected between the cooperative members of the clamps. The end portions of the strip or strips will be firmly gripped and held between the members of the clamps of the handle units when the nuts 11 have been tightened on the stud projections 7 and the device then will be ready for use. Since the members of each clamp have substantially flat surfaces next to the strip or strips which are gripped therebetween, it is obvious that in-

jury will not result to such strip or strips. The resistance that the device will oppose to such movement of the handle units apart as will cause a pull on the elastic connecting means between the handle units can be varied at will within a considerable range by varying the number of the strips of which the elastic connecting means between the handle units is composed. The device is simple in construction, reliable in use and effective for the purpose for which it is intended.

Obviously, my invention is susceptible of embodiment in forms other than that illustrated in the accompanying drawings and I therefore consider as my own all such modifications and adaptations of the form of the device herein described as fairly fall within the scope of the appended claims.

I claim:—

1. An exerciser of the character described comprising a pair of hand grip members, an elastic strip adapted to be stretched longitudinally and pairs of adjustably connected substantially flat cooperating jaws for connecting the ends of said strip with said hand grip members.

2. An exerciser of the character described comprising a pair of hand grip members, one or more strips of elastic material, each adapted to be stretched, and a clamp connected with each hand grip member and comprising a pair of adjustably connected substantially flat jaws, for releasably holding an end portion or portions of said strip or strips of elastic material.

3. An exerciser of the character described comprising an elongated flat strip of elastic material adapted to be stretched, a pair of handle units, each comprising a hand grip member, and a clamp connected with said hand grip member and comprising a pair of adjustably connected substantially flat jaws for gripping an end portion of said strip

of elastic material, one of said jaws being rigidly connected with said hand grip member.

4. An exerciser of the character described comprising a pair of handle units, each comprising a hand grip member, a clamp member connected at its ends with the ends of said hand grip member and disposed parallel to said hand grip member, said clamp member having a flat upper face, upstanding stud projections on the opposite end portions of said clamp member, a second clamp member having vertical openings in the end portions thereof through which said stud projections may extend, said second clamp member having a flat bottom face, and nuts threadedly engaged with the extending end portions of said stud projections, and an elongated elastic member having its ends held between the clamp members of said handle units.

5. An exerciser of the character described comprising a pair of handle units, each comprising a hand grip member, a clamp member connected at its ends with the ends of said hand grip member and disposed parallel to said hand grip member, said clamp member having a flat upper face, upstanding stud projections on the opposite end portions of said clamp member, a second clamp member having vertical openings in the end portions thereof through which said stud projections may extend, said second clamp member having a flat bottom face, nuts threadedly engaged with the extending end portions of said stud projections, the flat upper face of said first named clamp member lying in a plane which extends through said hand grip member below the longitudinal center line of the latter, and an elongated elastic member having its ends held between the clamp members of said handle units.

ROY H. NOE.
